GUANIDINE NAPHTHENATES AND PROCESS
FOR MAKING THEM

Allen F. Millikan, Crystal Lake, Ill., assignor to The Pure Oil Company, Chicago, Ill., a corporation of Ohio
No Drawing. Filed July 13, 1961, Ser. No. 123,639
13 Claims. (Cl. 208—180)

This invention relates to new and useful improvements in processes for the refining of crude petroleum fractions to reduce the amount of naphthenic acids present therein, and to novel naphthenate salts produced in the refining process.

Many crude oils contain sufficient quantities of naphthenic acids to make it necessary to modify refining procedures in order that products such as lubricating stocks and lubricating oils be essentially free of acids. In the refining of crude petroleum which contains substantial amounts of naphthenic acids, there is a problem of excessive corrosion in the distillation equipment due to the production of hydrogen chloride by reaction of naphthenic acids in the petroleum with trace amounts of inorganic chlorides in solution. In the past, attempts have been made to remove naphthenic acids from crude petroleum or from petroleum fractions at various points in the refining processes, or to convert the naphthenic acids into salts or esters. Prior methods dealing with naphthenic acids have included neutralization by alkali, esterification, catalytic decarboxylation of the acids, extraction with various phenols, alcohols, or other solvents, with or without neutralization, and clay treating. Numerous countercurrent solvent extraction processes have been proposed for use in refining petroleum oils. One process which has been used utilizes an extracting solution consisting of an alkylolamine dissolved in an aliphatic alcohol to react with and remove the naphthenic acids. Other methods have utilized esterification reagents to convert naphthenic acids into neutral esters which are left in the oil. Still another method which has been used for reducing the acidity of crude petroleum and petroleum fractions has utilized treatment with aqueous alkali to neutralize naphthenic acids, followed by separation of the aqueous solution of alkali metal and naphthenate salts. This process, however, has been ineffective with many types of petroleum and petroleum fractions which contain high-molecular-weight naphthenic acids, because the corresponding alkali metal naphthenates are preferentially oil-soluble and cannot be removed by washing with water or alcohol.

It is therefore one object of this invention to provide an improved process for reducing the acid neutralization number of crude petroleum and petroleum fractions containing substantial amounts of naphthenic acids which form alkali metal salts which are oil-soluble.

Another object of this invention is to provide an improved process for refining crude petroleum and petroleum fractions containing substantial amounts of naphthenic acids in which the naphthenic acids are converted into guanidine or substituted-guanidine salts which can be extracted in alcohol or aqueous alcohol solution.

Another object of this invention is to provide a novel class of naphthenate salts.

A feature of this invention is the provision of an improved process for refining crude petroleum, or a petroleum fraction containing substantial amounts of naph-

2

thenic acids, by treatment with a guanidine compound to produce a mixture of guanidine or substituted-guanidine naphthenates which are removed by extraction with alcohol or aqueous alcohol mixtures.

5 Another feature of this invention is the provision of an improved process for the refining of petroleum fractions which comprises mixing and heating the fraction with a slurry or solution of a guanidine compound in aqueous alcohol and removal of the resulting guanidine (or substituted-guanidine) naphthenates in the form of alcoholic solution.

Another feature of this invention is the provision of an improved process for reclaiming used crankcase oils in which the used oil is treated with a solid adsorbent to 15 remove asphaltic and tarry materials, and then is treated with a guanidine compound to remove acidic materials present in the oil.

Still another feature of this invention is the provision 20 of a novel class of naphthenate salts of guanidine and alkyl-substituted-guanidines.

Other objects and features of this invention will become apparent from time to time throughout the specification and claims as hereinafter related.

This invention is based upon my discovery that naphthenic acids can be removed from crude petroleum or 25 petroleum fractions by treatment with guanidine, substituted-guanidines, or salts (of weak acids) thereof. The guanidine or substituted-guanidine salts which are formed are removed by extraction with an alcohol or aqueous alcohol solution. It is well known that naphthenic acids present in crude oil, and in petroleum fractions such as lubricating oils and lubricating oil extracts, are not readily removable by washing the oils with aqueous alkali 30 solutions. In fact, these alkali naphthenates are soluble in oils to a much greater extent than they are in water. Since the acid neutralization number of crude oil and petroleum fractions is due largely to the presence of naphthenic acids, washing the oil with aqueous alkali solution is of little use for reducing the acid neutralization 35 number. I have found that the treatment of petroleum fractions containing naphthenic acids with guanidine compounds selected from the group consisting of guanidine, alkyl-substituted guanidines, and salts (of weak acids) thereof in alcohol or aqueous-alcohol solution (or slurry) converts the naphthenic acids into guanidine (or substituted guanidine) naphthenates which are readily 40 removed by alcohol or aqueous-alcohol solutions. In addition, the guanidine or substituted-guanidine naphthenates which are recovered are novel compounds which are useful for a variety of purposes. The guanidine and substituted-guanidine naphthenates are useful as detergents, per se, or in solution in oils, and are useful in increasing the resistance of lubricating oils to wear and produce a slight improvement in octane number when 45 mixed with gasolines.

In carrying out this process, sufficient guanidine, alkyl-substituted guanidine, or salts thereof, is added in solution in alcohol or aqueous alcohol (or any other suitable inert solvent) to neutralize the naphthenic acids present 50 in the crude oil or petroleum fraction. When oil-soluble guanidine compounds are used to react with the naphthenic acids, it is sufficient to use stoichiometric amounts of the reactant. When oil-insoluble salts of guanidine (or substituted guanidines) are used, the amount of the reactant should be greater than stoichiometric because of 55

the relative inefficiency of contact. In either case, it is desirable to agitate the reaction mixture to obtain intimate contact between the guanidine compound and the naphthenic acids. While guanidine is very effective in this process, its instability and the difficulties associated with its handling make it less suitable than certain derivatives. In carrying out this process, guanidine can be used although guanidine salts of weak acids such as guanidine carbonate, guanidine acetate, guanidine borate, etc., are preferred. Of these, the carbonate is preferred since the 10 carbonic acid formed breaks up into CO_2 and H_2O , whereas other acids may leave undesirable residues. Likewise, substituted guanidines, preferably alkyl-substituted guanidines, such as methylguanidine, dimethylguanidine, 15 tetramethylguanidine, ethylguanidine, tetraethylguanidine, tetrapropylguanidine, tetracyctylguanidine, etc., are also preferred because of their solubility in petroleum fractions which makes the reaction with naphthenic acids more efficient. The weak-acid salts of these substituted-guanidines can also be used in the process. Where 20 guanidine or substituted-guanidine salts are used as reactants, it is generally necessary to heat the reaction mixture and agitate the same in order to effect a decomposition reaction in which the guanidine or substituted-guanidine naphthenate is formed as a product. The 25 guanidine or substituted-guanidine naphthenates which are obtained in this manner are generally oil-insoluble, but are somewhat soluble in water and aqueous alcohol solutions.

Where this process is used for reducing the acid neutralization number of a crude oil, the treatment is preferably carried out prior to desalting the crude so that the aqueous-alcohol layer containing the water-soluble guanidine (or substituted-guanidine) naphthenate can be removed in the desalter. When this process is used in the treatment of refined petroleum fractions, the petroleum fractions are mixed with the guanidine compound and reacted as described above. This process is also applicable to the recovery and reclaiming of used crankcase oils. In such a process, the used oils are first filtered through a 30 granular adsorbent to remove asphaltic and tarry materials, and then are treated with the guanidine compound for removal of acidic components. The finished petroleum products which are obtained in this manner have low acid neutralization numbers, have increased resistance to oxidation and heat breakdown, and are more stable against color deterioration on extended storage. After 35 addition of oxidation inhibitor and sludge dispersants, these reclaimed fractions are equal to or even better than unused oils containing the same additives.

The following non-limiting examples are illustrative of the scope of this invention.

Example I

A petroleum fraction of high acidity was prepared by dissolving 33.1 g. of a commercial mixture of naphthenic acids (average molecular weight, 330) derived from petroleum (Sunaptic Acid B, manufactured by Sun Oil Company) in 130.1 g. of 85 vis. neutral oil. The resulting solution was dark in color and had an acid number of 33.4. A 31.0-ml. portion (27.4 g.) of the solution was mixed with 10 ml. (8.6 g., 0.075 equivalent) of tetramethylguanidine and 40 ml. of methanol in a 100-ml. mixing graduate. The mixture was agitated and then allowed to settle for 72 hours. At the end of this time, three phases had separated: an upper methanol phase having a volume of 65 ml.; a middle oily phase having a volume of 25 ml.; and a lower phase having a volume of 1 ml., consisting essentially of tetramethylguanidine naphthenate. The oily phase which was recovered was considerably improved in color and was slightly alkaline, apparently due to the presence of small amounts of dissolved tetramethylguanidine. This treatment resulted in the lowering of the acid number of the oil from 33.4 to 0 or even slightly alkaline. The residual tetramethylguanidine present in the oil and tetramethylguanidine

5 naphthenate which did not separate can be removed, if desired, by washing the oil with methanol.

The tetramethylguanidine naphthenate which is recovered is the tetramethylguanidine salt of the mixture of naphthenic acids which was present in the oil. Tetramethylguanidine naphthenate is slightly soluble in oil and improves the wear characteristics of a lubricating oil. Also, the tetramethylguanidine naphthenate has surfactant properties and is useful as a detergent.

Example II

A 20-ml. portion of the oil-acid mixture used in Example I (containing approximately 0.01 equivalent of acid) was shaken in a 100 ml. mixing graduate with 50 ml. of a 1:1 methanol-water mixture containing, in suspension, approximately 0.08 equivalent of guanidine carbonate. After the mixture had settled for 72 hours, three phases had separated, as in Example I: 13 ml. of an upper, oily phase; 12.5 ml. of a middle phase, consisting of a concentrated solution of guanidine naphthenate; and 44.5 ml. of a lower, aqueous-alcohol phase. Acidity measurements made on the oily phase revealed that the acid number had been reduced from 33.4 to less than 0.1. The color of the oil phase was substantially improved over that of the original oil-acid mixture.

Example III

A lubricating oil extract (having an acid neutralization number of 6.5), obtained by phenol extraction of a lubricating oil fraction, is treated in accordance with the subject invention. A 100-g. portion of this lubricating oil extract (from the manufacture of 170 vis. neutral) is agitated for 30 minutes with a slurry consisting of 10 g. guanidine carbonate in 20 ml. of 50% aqueous-methanol, while the temperature is gradually increased from room temperature to 180° F. The mixture is allowed to settle for 16 hours and the oil phase is washed with 50/50 aqueous-methanol. The oil phase which is recovered has an acid neutralization number of 0. The guanidine naphthenates which separate as a separate phase, and are removed with the aqueous-methanol, can be used in detergent compositions and as lubricating-oil additives. Also, the guanidine naphthenates can be washed with a strong acid, e.g., hydrochloric acid, sulfuric acid, etc., to recover naphthenic acids.

Example IV

A solution of 60 g. ($\frac{1}{2}$ mol, $\frac{2}{3}$ equivalent) of guanidine carbonate in 200 ml. of water was prepared and mixed with 200 ml. of methanol to produce a slurry for treatment of an acidic oil fraction. A solution consisting of 500 ml. (424 g.) of an oil consisting of 89.9% wt. of 85 vis. neutral oil and 10.1% wt. of a mixture of commercial naphthenic acids (Sunaptic Acid B) was 55 mixed with 200 ml. of the guanidine carbonate slurry and charged to a 1-liter separatory funnel and shaken vigorously. After standing several hours, two lower phases separated: an aqueous phase of about 100 ml. and a phase consisting of a solution of guanidine naphthenate 60 in aqueous alcohol.

The oily phase which remained was then shaken vigorously with the remaining slurry (200 ml.) of guanidine carbonate in aqueous methanol. After settling for several hours, there was about 230 ml. of aqueous phase 65 and about 25 ml. of a phase consisting of a concentrated solution of guanidine naphthenate. The oily phase was filtered several times through Reeve-Angel paper until clear (although substantially darker than the original neutral oil). The oil had an acid number less than 0.05 and a nitrogen content of less than 0.03%. The acid 70 number and nitrogen analysis indicated that substantially all of the naphthenic acids were removed and that guanidinium naphthenates were present in the oil in only a very small concentration.

75 The naphthenate and aqueous methanol phases recov-

ered from the treatment of the oil were mixed with water and benzene, and sodium chloride was added and shaken with the mixture. The guanidine naphthenate was thus salted out of the aqueous methanol and recovered as a benzene solution. The benzene phase was stripped with nitrogen under vacuum and guanidine naphthenate was recovered as a jet-black, viscous liquid. The product weighed 54.7 g.; the theoretical yield of guanidine naphthenate was calculated to be 55.2 g.

Example V

Four hundred ml. (339 g.) of 10.1/89.9 naphthenic acid-neutral oil mixture (prepared in accordance with Example IV) was charged to a 1-liter separatory funnel. One hundred ml. of methanol and 25 ml. (22.8 g., 0.20 equivalent) of tetramethylguanidine were added and the mixture shaken vigorously. After standing for several hours, two phases separated: an upper oily phase of 365 ml. and a lower methanol phase of 155 ml. (very dark in color and consisting of excess tetramethylguanidine and its naphthenate salt). The oil phase was filtered twice through double thicknesses of Reeve-Angel paper, and was found to have an ASTM color of +2, a nitrogen content of 0.09%, a total base number of 1.6, and a strong base number of 0.4. These analyses indicated that some free tetramethylguanidine was present in the oil together with some tetramethylguanidine naphthenate, but no free naphthenic acid was present.

The methanol phase was treated with water, benzene, and sodium chloride (as in Example IV). The benzene phase was recovered and subjected to vacuum-nitrogen stripping, to produce a product consisting essentially of tetramethylguanidine naphthenate. The product recovered weighed 45.2 g. as compared to a theoretical yield of 50.5 g. This product was inky black in color and only slightly less viscous than the product obtained in the previous example.

The oil phases from Examples I, II, III, and IV, containing a small amount of guanidine naphthenate or tetramethylguanidine naphthenate were tested for extreme pressure properties and resistance to oxidation. These oils were tested on a Shell Four-Ball Machine and found to produce a wear scar about 5% smaller than that produced by the base oil and a weld point about 10 kg. higher than for the base oil. This improvement in wear properties and weld point for the oil is obviously due to the presence of a small concentration of guanidine naphthenate or tetramethylguanidine naphthenate in the oil. Portions of the oil containing guanidine naphthenate and tetramethylguanidine naphthenate were subjected to the ASTM oxidation test, and the absorption of oxygen per hour per gram of oil was substantially less for oils containing the guanidine naphthenate or tetramethylguanidine salt than for the base oil.

While this invention is primarily concerned with the treatment of crude oil and virgin oil fractions, it is also applicable to the reclamation of used oils. Used oils, such as crankcase oils, have been reclaimed by various methods, including distillation to remove crankcase dilution, percolation through adsorbents to remove asphaltic and tarry materials, and distillation over alkali to remove most of the organic acids. Where the oils contain a substantial amount of bright stock or other non-distillable lubricating fractions, it has been difficult to reclaim all of the oil satisfactorily. When bright stock is present in the oil, distillation in the presence of alkali to remove acids (produced by partial oxidation of the oil during use) is not feasible. Thus, many reclaimed oils have relatively high organic acidities and may give trouble during use with certain types of bearings. In the following example it is seen how this process can be applied to the production of reclaimed oils having low acid neutralization numbers and containing substantially no asphaltic or tarry material, regardless of whether bright stock is present in the oil.

Example VI

A used crankcase oil, black in color and having an acid neutralization number of 3.1 is percolated through fuller's earth to remove asphaltic and tarry materials. The percolated oil is greenish-red in color and has an acid neutralization number of 0.7. A 1000-g. portion of the percolated oil is treated with 200 ml. of a slurry of 25 g. of guanidine carbonate in 50/50 aqueous methanol at 100° F. A mixture of oil and guanidine carbonate slurry is agitated for one hour and then allowed to settle for 6 hours. The mixture settles into two phases and the oil phase is recovered and washed with aqueous methanol. The treated oil is completely free of acid and has a very slight base number. This reclaimed oil has improved oxidation and color stability, and after addition of oxidation inhibitor and sludge dispersants to it, is equal to or even better than the unused oil containing the same oxidation inhibitor and sludge dispersants. The percolated crankcase oil can similarly be treated with tetramethylguanidine or other weak-acid salts of guanidine, or of tetramethylguanidine or other alkyl-substituted guanidines.

The used crankcase oil which is treated in accordance with this process cannot be converted to a product which is completely free of acid by merely percolating it through fuller's earth, or by distillation in the presence of caustic, or by a combination of the two steps. This oil is only about 40% distillable in the presence of caustic without substantial cracking.

While I have described my invention fully and completely with special emphasis upon several preferred embodiments, I wish it to be understood that within the scope of the appended claims this invention may be practiced otherwise than as specifically described herein.

The embodiments of the invention in which an exclusive property or privilege is claimed are defined as follows:

1. Naphthenate salts of compounds selected from the group consisting of guanidine and alkyl-substituted guanidines.
2. Guanidine naphthenate.
3. Alkyl-substituted guanidine naphthenates.
4. Tetramethylguanidine naphthenate.
5. A solution of compounds defined in claim 1 in a petroleum fraction.
6. A method of preparing compounds as defined in claim 1 which comprises mixing a guanidine compound selected from the group consisting of guanidine, alkyl-substituted guanidines, and weak-acid salts thereof, with a petroleum fraction containing naphthenic acids at a temperature sufficient to induce reaction and recovering the naphthenate salts thus formed.
7. A method in accordance with claim 6 in which the guanidine compound is added in an alcohol and the product naphthenates are recovered as an alcohol solution.
8. A method of refining a petroleum fraction containing a substantial amount of naphthenic acids which comprises mixing the fraction with a guanidine compound selected from the group consisting of guanidine, alkyl-substituted guanidines, and weak-acid salts thereof in an amount at least stoichiometrically equivalent to the naphthenic acids present at a temperature sufficient to induce reaction and neutralization of said naphthenic acids, and extracting the resulting naphthenate salts from the fraction.
9. A method in accordance with claim 8 in which the naphthenate salts are extracted with a solvent selected from the group consisting of lower alcohols and lower alcohol-water mixtures.
10. A method in accordance with claim 9 in which the guanidine compound is added to the petroleum fraction in admixture with the extracting solvent and the resulting mixture subjected to agitation.
11. A method in accordance with claim 10 in which the

petroleum fraction is treated with a solution of tetra-methylguanidine in methanol.

12. A method in accordance with claim 10 in which the petroleum fraction is treated with a slurry of guanidine carbonate in aqueous methanol.

13. In a method of reclaiming used crankcase oil in which the used oil is percolated through a granular adsorbent to remove asphalatic and tarry materials, the improvement which comprises treating the percolated oil in accordance with claim 8 to remove acidic impurities.
